BAG SEAL

Winfred M. Brooks, West Orange, N. J., assignor
to E. J. Brooks Company, Newark, N. J., a cor-
poration of New Jersey

Application May 5, 1938, Serial No. 206,217

7 Claims. (Cl. 292—308)

This invention relates to sealing means for bags of flexible material, such as the well-known canvas bags in which coin is transported, and has for its main object and feature the production of a sealing medium of the character indicated that is more secure and tamper-proof than those heretofore used.

In the accompanying drawing the invention is disclosed in several concrete and preferred forms 10 in which:

Fig. 1 is a view in elevation of one form of the improved sealing means;

Figs. 2 and 3 are views similar to Fig. 1, showing modified forms of the invention;

Fig. 4 is a perspective view of the gripping and severing member used in connection with the forms of the invention shown in Figs. 1 and 2;

Fig. 5 is a perspective view of the gripping and severing member used in connection with the 20 form of the invention shown in Fig. 3;

Fig. 6 is a perspective view of a member like that shown in Fig. 4 with a tag attached;

Fig. 7 is a detail view showing how a body of compressible material can be attached to the 25 gripping and severing member;

Fig. 8 is a view in elevation of the sealed bag;

Fig. 9 is a sectional view substantially on the plane of line 9—9 of Fig. 8; and

Fig. 10 is a detail view of a gripping and sever- 30 ing member having a pin.

In the art of sealing bags as heretofore practiced it has been the custom to pass a cord of flexible material around the bag, said cord being anchored in a body of relatively compressible material and to thread the cord through said body after which the body is compressed. Usually, said body carries a pin that projects into the bag to assist in preventing the cord from being slipped off the neck of the bag. This construction has not been altogether satisfactory because said body, usually of lead, can by manipulation have its openings enlarged thus permitting the cord to be slipped, after which access can be had to the interior of the bag and the cord can subsequently be retightened and the lead body recompressed without leaving evidence of the tampering.

Referring to Figs. 1 and 3, 1 indicates a cord of flexible material, 2 is the body of relatively compressible material such as lead, and 3 is a gripping and severing member of sheet material that is relatively rigid and non-compressible such as steel. It will be seen that the cord is anchored in the body of lead as by passing the end thereof through two openings 4 and 5 thereby forming

a loop 6, the free ends 7 and 8 being then threaded back through one or more openings 9 and 10 to form the relatively large loops 11 and 12 and these latter are passed around the neck of the bag. Member 3 is of generally cup-shape formation and is provided with one or more openings, here a slot 13, through which the free ends of the cord are threaded before said ends are threaded through openings 9 and 10 in the lead body. The openings in body 2 and member 3 preferably have their edges out of alignment with each other, this being accomplished in this instance by having slot 13 of less length than the distance between the outer edges of openings 4 and 5. Member 3 is so arranged that its concave portion 14 will be against the bag when the neck of the latter is encircled by loops 11 and 12. The sealing means as applied to the bag is shown in Figs. 8 and 9 where 15 indicates the bag, and from these figures it will be observed that, when the cord is tightened around the bag, part of the material thereof is forced into the cup-shaped portion or pocket of member 3 and that cord 1 is bent and forced against the edges of slot 13. Said member 3 therefore grips both the bag and the cord, the bag being gripped by the peripheral edges of member 3 and the cord being gripped by the edges of slot 13. Body 2 is now compressed. As the material of member 3 is stiff or rigid, its gripping effect is much more powerful than the grip of lead body 2 on the cord and it therefore offers much greater opposition to manipulation than said body 2. In addition, should it be attempted to insert a screw driver between the bag and the cord, in an attempt to loosen the cord, the edges of slot 13 will eventually sever the cord thereby leaving evidence of tampering. A further advantage is that when an authorized person cuts the cord to open the bag it is no longer necessary to insert the knife into the bag thereby mutilating the latter because now, on account of the convex portion of member 3 that is adjacent to body 2, the cord can be cut at a point between body 2 and member 3. It is not intended to convey that a pin 35 may not be used in addition to member 3, but it is believed to be unnecessary in most instances. If such a pin be used, it can be carried by body 2 in the usual way but, preferably as shown in Fig. 10, said pin 16 can be soldered to member 3, leaving an opening on each side of the solder for the threading of the cord. If desired, member 3 and body 2 can be attached to each other as shown for example in Fig. 7 where struck-up lugs 40 on member 3 are imbedded in body 2. So also, 45

an identifying tag 18 can be secured to member 3, as shown in Fig. 6, by means of prongs 19 on the edge of member 3. It will be observed that the tag, in addition to having an opening 20 through which the cord can pass, is also slotted at 21 so that it will not tear when tightening the cord around the bag.

If a small bag is used then, in order to avoid the necessity of having a member 3 of smaller size, it may be desirable to thread the cord the reverse of the arrangement shown in Fig. 1. As shown in Fig. 2, the cord is anchored by passing it first through openings 9 and 10 and subsequently through openings 4 and 5, which arrangement seems to spread the smaller amount of material more effectively against the cord which in turn is pressed against the edges of slot 13. In Figs. 3 and 5, the threading can be like that in Fig. 1 or Fig. 2. In this form of the invention, member 3 is provided with three openings, a center opening 22 and two smaller openings 23 and 24 whereby a greater number of wearing or severing surfaces or edges is afforded the cord.

25 I claim:

1. A sealing means for the mouth of a bag of flexible material including: a cord of flexible material to be tightened around the bag to constrict the same; a body of relatively compressible material in which the cord is anchored and through which said cord is threaded, the body being compressed around said cord; and a cup-shaped member of relatively rigid and incompressible sheet material, through which the cord is threaded, interposed between the bag and the body of compressible material with its concave portion adjacent the bag.

2. A sealing means for the mouth of a bag of flexible material including: a cord of flexible material to be tightened around the bag to constrict the same; a body of relatively compressible material in which the cord is anchored, said body having openings through which said cord is threaded, the body being compressed around said cord; and a cup-shaped gripping and severing member of relatively rigid and incompressible sheet material, having an opening through which the cord is threaded, the edges of which opening are out of alignment with those of the openings in said body, interposed between the bag and the body of compressible material with its concave portion adjacent the bag, into which concave portion some of the material of said bag is forced when the cord is tightened around the bag.

3. A sealing means for the mouth of a bag of flexible material including: a cord of flexible material to be tightened around the bag to constrict the same; a body of relatively compressible material in which the cord is anchored and through which said cord is threaded, the body being compressed around said cord; and a member of relatively rigid and incompressible sheet material, through which the cord is threaded, interposed between the bag and the body of compressible material to grip both the material

of the bag and the cord when the latter is tightened around the bag.

4. A sealing means for the mouth of a bag of flexible material including: a cord of flexible material to be tightened around the bag to constrict the same; a body of relatively compressible material in which the cord is anchored and through which said cord is threaded, the body being compressed around said cord; and a member of relatively rigid and incompressible sheet material, interposed between the bag and the body of compressible material, having an opening, presenting gripping and severing surfaces, through which opening the cord is threaded and against which surfaces the cord is pressed by the material of the bag when the cord is tightened around said bag.

5. A sealing means for the mouth of a bag of flexible material including: a cord of flexible material to be tightened around the bag to constrict the same; a body of relatively compressible material in which the cord is anchored and through which said cord is threaded, the body being compressed around said cord; and a cup-shaped member of relatively rigid and incompressible sheet material, through which the cord is threaded, interposed between the bag and the body of compressible material with its convex portion adjacent the body of compressible material to afford, between said member and the body of compressible material, an exposed portion of the cord.

6. A sealing means for the mouth of a bag of flexible material to be tightened around the bag to constrict the same; a body of relatively compressible material in which the cord is anchored, said body having openings through which said cord is threaded, the body being compressed around said cord; and a cup-shaped gripping and severing member of relatively rigid and incompressible sheet material, having a plurality of openings through which the cord is threaded, the edges of which openings are out of alignment with those of the openings in said body, interposed between the bag and the body of compressible material with its concave portion adjacent the bag, into which concave portion some of the material of said bag is forced when the cord is tightened around the bag.

7. A sealing means for the mouth of a bag of flexible material including: a cord of flexible material to be tightened around the bag to constrict the same; a body of relatively compressible material in which the cord is anchored and through which said cord is threaded, the body being compressed around said cord; and a member of relatively rigid and incompressible sheet material, interposed between the bag and the body of compressible material, having a plurality of openings, presenting gripping and severing surfaces, through which openings the cord is threaded and against which surfaces the cord is pressed by the material of the bag when the cord is tightened around said bag.

WINFRED M. BROOKS. 65
